UNITED STATES PATENT OFFICE.

EBENEZER BANTON BURR, OF LONDON, ENGLAND.

CIGAR OR CIGARETTE HOLDER.

SPECIFICATION forming part of Letters Patent No. 446,377, dated February 10, 1891.

Application filed July 5, 1890. Serial No. 357,823. (No model.)

To all whom it may concern:

Be it known that I, EBENEZER BANTON BURR, a subject of the Queen of Great Britain, residing at London, England, have invented new and useful Improvements in Cigar or Cigarette Holders, of which the following is a specification.

This invention relates to cigar or cigarette holders composed wholly of glass or other plastic material which can be worked into the desired form or shape while warm and becomes hard and practically rigid on cooling.

The invention has for its object to provide a novel cigar or cigarette holder composed wholly of glass and made of two separately-formed sections, a holder-body, and a tube, the body at one extremity being permanently sealed or joined to a shouldered part of the tube at a point on the latter remote from its two ends, whereby one end portion of the tube projects longitudinally from the body to form a mouth-piece, and the opposite end portion extends longitudinally into the holder-body to provide a surrounding nicotine-collecting chamber whereby the nicotine is excluded from the mouth of the user.

The invention also has for its object to provide a novel construction of this type of inflexible holder, whereby the nicotine-collecting chamber can be readily and conveniently cleaned without the necessity of withdrawing or otherwise disturbing the tubular extension in the holder-body, as must be done to properly clean those cigar-holders which are composed of a single piece of soft rubber having one tubular end doubled or turned back into the holder-body to provide a nicotine-collecting chamber.

The objects of my invention I accomplish in the manner and by the means hereinafter described and claimed, reference being made to the accompanying drawings, in which—

Figure 1 is a sectional side elevation showing the holder body and tube separated prior to being permanently sealed together or connected and shaped. Fig. 2 is a longitudinal sectional view of the finished cigar or cigarette holder.

In order to enable those skilled in the art to make and use my invention, I will now describe the same in detail, referring to the drawings, wherein—

The numeral 1 indicates the hollow body of the cigar or cigarette holder, which is composed of glass blown or molded into cylindrical form and drawn at one end 2 into tapering form to reduce its diameter and provide a contracted center orifice 3, of considerably less size than the internal caliber of the cylinder part of the holder-body. 55

The numeral 4 indicates a glass tube blown or molded into shape and drawn from near the middle of its length to one end to form a reduced hollow extension or neck 5 and create an annular projecting collar, shoulder, or 60 enlargement 6. The hollow extension or neck is inserted lengthwise through the center orifice in the contracted tapering end of the holder-body, so that the annular collar or shoulder on the tube 4 bears squarely against 70 the edge of the center orifice. The hollow body and the tube being warm and consequently plastic, the tube is pressed lengthwise, thereby conforming the edge of the center orifice and the annular collar or shoulder 75 to each other and permanently sealing them together through the medium of an ordinary blow-pipe. The external projecting end of the tube is then properly shaped by heat and pressure into the form desired for the mouth-piece 7, the construction being such that the holder when cool is inflexible and practically rigid, while one end portion projects longitudinally as the mouth-piece 7, and the opposite end portion extends longitudinally in the 85 center of the holder-body to provide an annular chamber 8 for collecting the nicotine and thereby excluding the same from the mouth of the person using the holder. 80

The construction permits the nicotine-collecting chamber to be readily, conveniently, and thoroughly cleaned, since free access can be had thereto from the cigar-receiving end of the holder, and there is ample space around the tube instead of a narrow or contracted 90 chamber, as heretofore.

The holder comprises two sections separately made; but the permanent sealing or connection of the holder-body to the tube intermediate the ends of the latter produces a 95 finished article which is practically a single piece. The parts are preferably made of transparent glass, whereby the interior is visible, while glass is readily cleaned; but I may

employ other plastic material—such as nitro-cellulose or other pyroxyline compounds—which can be properly worked while in a warm condition and set or harden on cooling.

5 Having thus described my invention, what I claim is—

A cigar or cigarette holder consisting of a hollow holder-body having a contracted extremity, and a tube permanently joined in-
10 termediate its ends to the contracted extremity of the holder-body and having one

end projecting longitudinally to form a mouth-piece and the other end extending centrally within the holder-body to provide a nicotine-collecting chamber, substantially as 15 described.

In testimony whereof I affix my signature in presence of two witnesses.

EBENEZER BANTON BURR.
